ELECTRODYNAMIC HAND MICROPHONE OF
THE PRESSURE GRADIENT TYPE

Robert K. Duncan, Mount Ephraim, N. J., assignor to Radio Corporation of America, a corporation of Delaware

Application August 25, 1949, Serial No. 112,227

9 Claims. (Cl. 179—115.5)

1

This invention relates to electro-acoustical transducers, and more particularly to noise cancelling, pressure gradient responsive microphones of the close talking type.

My present invention has been made especially with the idea of providing a close talking microphone for use in locations where there is considerable noise, such, for example, as those involving military operations. In many cases, microphones are used in the proximity of navigation equipment, or in the presence of other instruments which are particularly affected by a magnetic field. In these cases, it is essential that the microphone have a minimum external stray magnetic field, the requirements often being that the instrument should not deflect a compass needle more than two degrees at a distance of eight inches from the microphone. Another factor to be considered is that involving humidity which, in many cases, creates spurious or irregular response.

Many prior art close talking microphones have been proposed to solve problems involving the presence of external stray magnetic flux, among the more common being those using a soft iron cap or shield which will create a low reluctance path for the external leakage flux lines. While this method is satisfactory for many applications, it has a disadvantage in one respect in that it tends to reduce the density of magnetic flux in the air gap. Another disadvantage is the difficulty of providing sufficient shielding to meet rigid specification requirements.

The primary object of my present invention is to provide an improved, noise cancelling, pressure gradient responsive microphone of the close talking type which will overcome the above, as well as other, disadvantages of prior art close talking microphones.

It is also an object of my present invention to provide a close talking microphone which is highly discriminatory against ambient noise.

Another object of my invention is to provide a noise cancelling, close talking microphone having a balanced magnetic circuit with substantially no external stray magnetic field.

Still another object of my present invention is to provide a close talking microphone which will readily adapt itself to all changes in humidity.

A further object of my present invention is to provide a pressure gradient responsive, close talking microphone which is compact in construction, easily portable, and highly efficient in use.

In accordance with my present invention, I

2

provide a pressure gradient responsive microphone having a symmetrical magnetic structure disposed on opposite sides of a disc diaphragm. The magnetic structure comprises a pair of cylindrical, magnetic units each having an annular air gap disposed in an end thereof, the air gap ends being recessed from the peripheral edges of the cylindrical outer casing. The two magnetic units are mounted end to end along a common axis with their adjacent ends abutting to provide magnetic coupling between the two units thereby to obtain a balance of magnetic flux in the two air gaps supplied from suitable magnetic cores which are disposed within each of the units in conventional manner. A disc diaphragm responsive to differences in sound wave pressure on opposite sides thereof is mounted intermediate the recessed ends in spaced relation thereto and having separate voice coils mounted on opposite sides thereof and arranged for disposition within the annular air gaps. Openings are provided in the cylindrical outer casings, as well as in the recessed ends, to permit sound waves to impinge on opposite sides of the diaphragm. The two magnetic units are mounted for independent rotation with respect to each other about their common axis so that the casing apertures may be spaced apart circumferentially, thereby to provide an adjustable sound wave path length to opposite sides of the diaphragm thus enabling a user of the microphone to adjust it to eliminate undesirable response.

The novel features of my invention, as well as additional objects and advantages thereof, will be better understood from the following detailed description of one embodiment thereof when read in connection with the accompanying drawings, in which:

Figure 1 is a front elevation of a hand held microphone in accordance with my present invention.

Figure 2 is a side elevation of the microphone shown in Figure 1.

Figure 3 is an enlarged end view of the internal microphone structure, one of the magnetic units being removed to show the diaphragm, and

Figure 4 is an enlarged, central sectional view of the microphone structure shown in Figure 1, taken on the line 4—4 of Figure 1.

Referring more particularly to the drawing, wherein similar reference characters designate corresponding parts throughout, there is shown a noise cancelling, pressure gradient responsive, hand held microphone 1 comprising, generally, a cylindrical microphone structure 3 and a hand

support member 5. The cylindrical microphone structure 3 has separate cylindrical magnetic units or structures 7 symmetrically disposed on opposite sides of a vibratile member or disc diaphragm 9 to provide balanced magnetic circuits on opposite sides thereof, the magnetic structures being mounted end to end along a common axis. Each magnetic structure 7 comprises an annular receptacle or cup-shaped member 11 of magnetic material with a magnetic core 13 concentrically mounted on the interior of the base or outer end 15. An annular recess 17 is provided around the inner peripheral edge at the open end of each cup shaped member 11. A disc-like pole plate member 19 is disposed within each annular recess 17, each plate 19 having a diameter substantially equal to that of the recess 17. Each circular pole plate member 19 is provided with a central aperture 21 and a plurality of smaller apertures 23 surrounding the central aperture and constitutes an outer pole plate of the magnetic structure. A cylindrical pole cap 25 of magnetic material is mounted on the free end of each magnetic core 13, extending within the associated central aperture 21 in spaced relation to the plate member 19 to provide an annular air gap 27 therebetween. The polarity of corresponding parts of each magnetic structure 7 is so arranged that it is the same, that is, each of the circular pole plate members 19 is of the same polarity, and each magnetic core end disposed within its associated pole plate member central aperture 21 is likewise of the same polarity which is opposite to that of the circular pole plate members 19.

The disc diaphragm 9 is of a diameter substantially equal to that of each pole plate member 19, the central portion thereof being substantially flat except for outwardly extending portions 29 at the center thereof which are arranged in the form of a clover leaf, the purpose of this being to add rigidity to the central portion. In order to effect a well balanced acoustic structure, the portions 29 are symmetrically arranged around the center of the diaphragm and with adjacent portions extending outwardly in opposite directions. Radial corrugations 31 are provided adjacent the margin of the disc diaphragm 9 for the purpose of flexibly supporting the diaphragm central portion for freedom of movement in directions perpendicular to the plane in which the diaphragm lies. As seen in Figure 4 of the drawing, the radial corrugations 31 are symmetrically disposed on opposite sides of the plane of the diaphragm to effect an acoustically balanced structure. Separate voice coils 33 are concentrically mounted on opposite sides of the disc diaphragm 9 for disposition within the air gaps 27, their electrical outputs being connected to produce an additive effect.

In order to facilitate assembly of the component parts of the microphone 3, and in order to insure that the voice coils 33 will be centered within the air gaps 27, it has been found advantageous to mount the outer pole plate members 19 and the disc diaphragm 9 as a unit. As shown in Figure 4, the disc diaphragm 9 is disposed between the outer pole plate members 19, being supported at its periphery between a pair of annular spacing rings 35 of non-magnetic material, such as brass, which are mounted between the peripheral portions of the pole plate members 19, thereby to space the diaphragm 9 equally from each of the pole plate members 19 so that the diaphragm center portion will be

free to move without touching the pole plates. The pole plates 19, spacing rings 35 and the disc diaphragm 9 are substantially all of the same outer diameter as the diameter of the annular recess 17, and their combined thicknesses are substantially equal to the combined depths of both annular recesses 17 when the two magnetic structures 7 are mounted end to end. In order to maintain the diaphragm and pole plate unit in assembled relation, a plurality of screws 37 are provided adjacent the outer edge, being so disposed and arranged as to securely hold the parts together.

The assembled microphone 3 comprises a hollow cylindrical casing consisting of a pair of magnetic units or structures 7 mounted end to end with their adjacent ends 39 abutting, and with the diaphragm 9 dividing the interior of the microphone 3 into separate, substantially acoustically balanced chambers or compartments 41. In order that sound waves may be transmitted to opposite sides of the disc diaphragm 9, sound openings 43 are provided in the casing walls of the magnetic structures 7, being located adjacent to the plate members 19 on the side thereof remote from the diaphragm 9. For the purpose of providing damping, as well as to prevent dirt particles from entering the structure, suitable damping material 45, such as felt or hair, is disposed within the openings 43, or, in the event a screen such as silk, or the like, is found preferable, the same may be mounted on the interior casing wall and disposed over the openings. In order to achieve a more desirable frequency response, the acoustical circuit provided by the relatively large cavities or chambers 41 within the casings is modified by filling the cavities or chambers a desired amount with wax, "Bakelite," or other suitable material 47.

While it is intended that both magnetic structures 7 be made identical, it is obvious that the magnetic flux density in each air gap, when considered separately, would not ordinarily always be the same. However, by magnetically coupling the two structures end to end, in the manner described, the magnetic potentials across the air gaps will effect a balance of flux density in both air gaps. It is conceivable that when the two magnetic structures are abutted end to end, there will not be as perfect a contact between the abutting surfaces as would be desired because of minute variations which are encountered in the process of manufacture and assembly. In order to effect a more perfect coupling between the two magnetic structures and hence effect an efficient, well balanced magnetic structure on both sides of the diaphragm, a ring 48 of magnetic material is closely fitted around the magnetic structures 7 and connecting their abutted ends. Furthermore, the ring 48 also assists in maintaining alignment of the two magnetic structures 7. In addition thereto, since the respective elements of both magnetic structures 7 are of like polarity, there will exist a "bucking" or repellent action between the two magnetic structures when mounted end to end. As a result of this "bucking" action, part of the normal external leakage flux in the vicinity of the pole plate ends will be forced back into the air gap and this will increase the magnetic flux density in each air gap. One microphone, constructed in accordance with my invention, showed as much as 12% increase in magnetic flux density in each air gap. Hence, the total output of such a microphone with the voice coils connected to

produce an additive effect is considerably increased and may be found to be approximately 25% greater than the output of two separate microphone structures, or that obtained from a single structure proportionately larger.

Inasmuch as this type of microphone is responsive to sound waves only when there exists a difference in pressure on opposite sides of the diaphragm, it becomes necessary to provide a difference in sound wave path length to opposite sides of the diaphragm from the desirable sound source. For this purpose, one magnetic structure 7 is made independently rotatable with respect to the other so that the spacing between the sound openings 43 may be varied. In order that this may be done, and further in order to prevent separation of the two magnetic structures in axial directions, the hand held support 5 is arranged to engage opposite ends of the microphone. For the purpose of illustration, the hand support 5 is shown herein as comprising a bifurcated member 49 disposed on one end of a handle 50. A pair of set screws 51 are threadedly mounted within and adjacent to the bifurcated ends of the support 5, each screw 51 having a pointed end 53 which provides a bearing surface for engaging a complementary detent disposed in the adjacent end of the microphone 3. With this arrangement, either unit 7 of the entire microphone 3 may be rotated with respect to the member 49. Thus, when the microphone is held in front of the mouth, the user may rotate either unit relative to the other to orient or dispose its opening 43 directly in front of his mouth and sound waves may be transmitted directly into that opening along the shortest path thereto. This mounting arrangement will also permit the two magnetic structures to be rotated with respect to each other thereby to separate the openings 43 circumferentially about the cylindrical casing any desired amount. In order to limit rotation of either magnetic structure 7, thereby to prevent breaking the leads 55 from the voice coils, stops 57 are provided on the magnetic structures 7 as well as on the bifurcated ends of the hand support 5.

Providing an adjustable sound wave path length between the two sides of the diaphragm is a particularly desirable feature of my improved noise cancelling, pressure gradient responsive microphone. It is well known to those persons skilled in the art that this type of microphone ceases to operate correctly as a pressure gradient responsive device as the frequency of the sound wave approaches such a value that the path length from one side of the diaphragm to the other side of the diaphragm is an appreciable portion of the wavelength. The generally accepted limit for correct operation is taken to be that point at which the path length front to back of the diaphragm is one quarter wave length. For example, a microphone as herein described, with a path length of one-half inch, would efficiently cancel ambient noise up to about 7000 cycles per second where the ambient or random noise originates at a relatively remote point from the microphone, whereas one having a path length of one-quarter inch would efficiently cancel ambient noise up to about 14,000 cycles per second, under the same conditions. It is readily seen that the shorter the path length between the two surfaces of the diaphragm, the higher will be the limit of high frequency cancellation for sounds originating at a remote point. There-

fore, it would be desirable to keep this path length as short as possible.

On the other hand, one must also be able to direct the desired sound more strongly to one side of the diaphragm than to the other in order that the microphone will reproduce the desired sounds. It is obvious, therefore, that the shorter the front to back sound wave path length, the more cancellation of desirable sounds takes place and there results a lower electrical output. Thus, to pick up desirable sound waves, the front to back path length should be as long as possible.

Considering these two contradictory factors, it is readily seen that a microphone with a variable sound wave path length is desirable. Under extreme conditions of high frequency noise, a short path length would be desirable, even though a somewhat decreased electrical output would be tolerated. Under different conditions, where the noise is predominately of low frequency, one could increase the path length and obtain a gain in desired electrical output without appreciably decreasing the signal to noise ratio.

Thus, it will be evident to those persons skilled in the art, that I have provided an efficient, noise cancelling, pressure gradient responsive microphone which has substantially no external stray magnetic field, and one which has an increased output over other pressure gradient responsive microphones comparable in size. It will also be recognized that the microphone is simple and easy to construct, and, with suitable choice of materials, it may be made relatively small in size.

While I have shown and described but a single modification of a pressure gradient responsive microphone in accordance with my present invention, it will become obvious to those persons skilled in the art that other modifications and changes are possible within the spirit of my invention. Therefore, I desire that the particular form of my invention described herein be considered as illustrative and not as limiting.

What is claimed is:

1. A pressure gradient responsive microphone of the moving coil type comprising a casing of magnetic material, a diaphragm mounted within said casing and dividing the interior thereof into separate chambers on opposite sides of said diaphragm, magnetic structures including said casing symmetrically disposed on opposite sides of said diaphragm and providing balanced magnetic circuits on opposite sides of said diaphragm, said magnetic structures including a pair of air gaps, one in each of said chambers, and coil means carried by said diaphragm on opposite sides thereof, said coil means being disposed each in a separate one of said air gaps, and said casing being provided with spaced apertures communicating separately with each of said chambers.

2. A pressure gradient responsive microphone of the moving coil type comprising a casing of magnetic material, a diaphragm mounted within said casing and dividing the interior thereof into substantially acoustically balanced chambers on opposite sides of said diaphragm, magnetic structures including said casing symmetrically disposed on opposite sides of said diaphragm and providing balanced magnetic circuits on opposite sides of said diaphragm, said magnetic structures including a pair of air gaps, one in each of said chambers, and coil means carried by said diaphragm substantially centrally thereof and in coaxial relation equally on opposite sides thereof, said coil means being disposed each in a separate

one of said air gaps, said casing being provided with spaced apertures communicating separately with each of said chambers, and said magnetic structures being rotatable with respect to each other for varying the spacing between said apertures.

3. A pressure gradient responsive microphone according to claim 2 characterized in that said magnetic structures are of corresponding polarity.

4. A pressure gradient responsive microphone of the moving coil type comprising a casing of magnetic material, a diaphragm mounted within said casing and dividing the interior thereof into substantially acoustically balanced chambers on opposite sides of said diaphragm, separate magnetic structures including said casing symmetrically disposed on opposite sides of said diaphragm and providing balanced magnetic circuits on opposite sides thereof, said magnetic structures including two substantially equal air gaps disposed centrally and coaxially on opposite sides of said diaphragm, and coil means carried by said diaphragm centrally on opposite sides thereof and disposed within said air gaps, said coil means on opposite sides of said diaphragm being electrically connected to produce an additive effect, said casing being provided with spaced apertures communicating separately with each of said chambers, and said magnetic structures being rotatable with respect to each other for varying the spacing between said apertures.

5. A pressure gradient responsive microphone according to claim 4 characterized in that said casing comprises a pair of cup-shaped members each having a recess disposed around the inner peripheral edge at the open end thereof, said cup-shaped members being coaxially mounted with the open ends thereof abutting, characterized further by the addition of plate members each having a plurality of apertures therein, said plate members constituting outer pole plates disposed respectively within said recesses, one of said apertures in each plate member being centrally disposed, and characterized further in that said magnetic structures include magnetic core means attached to each of said cup-shaped members, each core means having one end thereof disposed

within the central aperture of its associated plate member in spaced relation to its said associated plate member to provide one of said air gaps therebetween.

6. A pressure gradient responsive microphone according to claim 5 characterized in that each of said outer pole plates is of the same polarity, and further characterized in that each said magnetic core means end disposed within its associated plate member central aperture is of the same polarity and opposite to that of said outer pole plates.

7. A pressure gradient responsive microphone according to claim 5 characterized in that said diaphragm is supported at the peripheral edge thereof between said cup-shaped members and is disposed between said outer pole plates in equal, spaced relation thereto.

8. A pressure gradient responsive microphone according to claim 7 characterized in that said casing apertures are disposed in the walls of said cup-shaped members adjacent to said outer pole plates on the sides thereof remote from said diaphragm, and further characterized in that the remainder of said outer pole plate apertures comprise passages for sound waves entering said chambers through said casing apertures to opposite sides of said diaphragm.

9. A pressure gradient responsive microphone comprising a diaphragm responsive to differences in sound wave pressure on opposite sides thereof, separate magnetic structures disposed in abutting relation to provide an enclosed casing for said diaphragm, said magnetic structures being symmetrically disposed on opposite sides of said diaphragm and supporting said diaphragm at its periphery, said magnetic structures including a pair of air gaps, one on each side of said diaphragm, and coil means attached to said diaphragm on opposite sides thereof, said coil means being disposed each in a separate one of said air gaps, said casing having apertures therein for transmitting sound waves to opposite sides of said diaphragm, and said magnetic structures being rotatable with respect to each other for varying the spacing between said apertures.
